UNITED STATES PATENT OFFICE

162,859

ADVERTISING DISPLAY DEVICE

Athanasiros K. Mellos, Los Angeles, Calif.

Application May 16, 1950, Serial No. 9,969

Term of patent 7 years

(Cl. D1—2)

To all whom it may concern:

Be it known that I, Athanasiros K. Mellos, a citizen of the United States, residing at Los Angeles, county of Los Angeles, and State of California, have invented a new, original, and ornamental Design for an Advertising Display Device, of which the following is a specification, reference being had to the accompanying drawings, forming a part thereof.

Fig. 1 is a side elevation of an advertising display device, showing my new design, showing one side thereof, Fig. 2 is a side elevation showing a second side, Fig. 3 is a top plan view, Fig. 4 is a side elevation showing a third side, and Fig. 5 is a side elevation showing a fourth side thereof.

I claim:

The ornamental design for an advertising display device, as shown.

ATHANASIOS K. MELLOS.
